UNITED STATES PATENT OFFICE.

A. JOSEPH NURRE, OF CINCINNATI, OHIO.

MOUNT FOR CHROMOS AND OTHER ILLUSTRATIONS.

SPECIFICATION forming part of Letters Patent No. 236,244, dated January 4, 1881.

Application filed April 8, 1880. (No model.)

To all whom it may concern:

Be it known that I, A. JOSEPH NURRE, of Cincinnati, Hamilton county, Ohio, have invented a certain new and useful Improvement 5 in Mounting Prints, Chromos, Show-Cards, and Similar Illustrations, of which invention the following is a specification.

The usual method of mounting chromos, show-cards, &c., is to paste or glue them on 10 a piece of canvas attached to a wooden frame termed a "stretcher," but this procedure is objectionable for several reasons. In the first place the stretcher requires considerable labor to make it square and perfectly secure at 15 the miter-joints, and after being carefully constructed it is liable to be twisted out of shape when the canvas and mounted chromo contract in drying; secondly, a print or chromo, when thus mounted, is liable to absorb moisture 20 at the back or unvarnished surface, which absorption soon causes the picture to wrinkle or buckle, and thereby lose its attractive appearance; thirdly, according to the old method of mounting, the picture is not supported by 25 any firm backing, and therefore it is liable to have a hole punched through it if struck by any passing object; fourthly, the stretchers occupy valuable space and add materially to 30 the weight of the packing-box, and thus increase the cost of transportation, to say nothing about the original expense attending the manufacture of such frames. These and other well-known objections incidental to the use of 35 stretchers have induced me to contrive a backing for chromos, prints, &c., that effectually overcomes all the difficulties attending the mounting of such pictures. This backing, in its more simple form, consists of two thin pieces of wood with their surfaces glued or 40 otherwise permanently fastened together, so that the grain of one piece is about at right angles with the grain of the other piece, which construction affords a cheap, light, firm, and durable support, to which the picture is cemented in any approved manner, as hereinafter 45 more fully described.

In the annexed drawings, Figure 1 is a perspective view, showing the two parts of my backing detached from each other. Fig. 2 is 50 a perspective view, showing these two pieces of stuff secured together and a chromo mount-

ed thereupon, a portion of the chromo and of the front piece of backing being broken away. Fig. 3 is a vertical section of a more elaborate form of my invention.

A and B represent, respectively, two thin pieces of stuff, such as ordinarily used as backing for prints, &c., of which pieces the exposed surface of the front one should be smooth, even, and free from perforations or 60 holes, while the other surfaces need not be so well finished. Although it is preferred that the front veneer, B, should be free from perforations or deep grooves or other irregularities, yet these precautions need not be observed with reference to the back veneer, A, or to any of the additional pieces of stuff secured to said backing, as it is evident the smoothness and safety of the picture are not impaired by any roughness of the rear veneers. Consequently the back veneer or veneers may be made of inferior stuff containing knot-holes or cracks, or other flaws or openings. These two pieces are glued or otherwise permanently attached to each other in such a manner that 75 the grain of the backing A will be about at right angles with reference to the grain of the other backing, B, as seen in Fig. 2. After being thus attached together, the chromo, print, or card C is glued or cemented to the smooth 80 front surface of the piece B, when the picture is at once ready to receive the final coat of size and varnish and be packed for transportation.

As the grain of backing A is about at right 85 angles with reference to the grain of the backing B, it is evident that any tendency of the former to warp is resisted by the tendency of the latter to warp in an opposite direction, and vice versa. Consequently these two opposing 90 forces exactly neutralize each other, and the result is, that the backing remains perfectly flat and even for an indefinite period of time, and never shrinks or cracks. Furthermore, this composite backing is light and cheap, obviates the use of canvas, and prevents the picture absorbing moisture and becoming buckled or wrinkled. It facilitates packing, cheapens transportation, and prevents a hole being punched through the chromo by contact with 95 a projection of any kind.

This invention may be modified by the ad-

dition of another piece of stuff, D, to the back of the one A, and, if preferred, a fourth or fifth piece may be employed for a picture of unusual size.

5 I am aware it is not new to cut tracery, scrolls, &c., through pieces of veneers, and then attach a number of such perforated veneers together with their grain crossed and apply to the same an ornamental backing, so as to 10 constitute a mat for picture-frames, as such a device is seen in Letters Patent No. 156,788, issued to H. S. Hale, November 10, 1874. Furthermore, I am aware it is not new to manufacture chair-seats, trunk-bodies, plates, and 15 various other articles of a number of pieces of veneers with their grains crossed. Finally, I am aware it is not new to secure together two or more layers of thin wood with their grains crossed, and then attach these united veneers 20 to a frame and apply to the exposed surface of this composite structure a suitable ground to paint on, so as to afford a substitute for artists' canvas, as such a device is illustrated and described in Letters Patent No. 229,244, 25 issued June 29, 1880, to E. F. French.

Such being the state of the art, my claim is not designed to cover such composite structures for all kinds of ornamental purposes, but is ex-

pressly limited to the construction herein described, whereby any print, chromo, show- 30 card, or other picture is mounted on a veneer, to which latter one or more thin pieces of stuff are secured with their grain crossed, the outer veneer upon which the picture is mounted being free from tracings or scrolls, or any large 35 opening or openings, and the exposed face of the picture being protected with a transparent varnish.

I claim as my invention—

As a new article of manufacture, a chromo, 40 print, or show-card permanently secured to a "mount" composed of two or more thin pieces of wood attached to each other with their grains crossed, the outer veneer to which the picture is applied being free from tracings or 45 scrolls, or any large opening, and the exposed face of the picture being protected with a transparent varnish, substantially as herein described, and for the purpose set forth.

In testimony of which invention I hereunto 50 set my hand.

A. JOSEPH NURRE.
